UNITED STATES PATENT OFFICE.

GEORGE HENRY WHEARY, OF RACINE, WISCONSIN.

LOCKING-FIXTURE FOR TRUNKS.

1,208,061.

Specification of Letters Patent. Patented Dec. 12, 1916.

Application filed July 1, 1915. Serial No. 37,406.

To all whom it may concern:

Be it known that I, GEORGE HENRY WHEARY, a citizen of the United States, and resident of Racine, in the county of Racine and State of Wisconsin, have invented new and useful Improvements in Locking-Fixtures for Trunks, of which the following is a description, reference being had to the accompanying drawings, which are a part of this specification.

My invention relates to improvements in locking fixtures for trunks, more particularly trunks of the wardrobe type.

In trunks of the wardrobe type, one of the sections is usually provided with a number of drawers placed one above the other, and if the drawers are not locked in closed position they will slide back and forth in their places during transportation, and ultimately will injure or mar the face of the other trunk section, and other parts against which they strike. This trouble may be overcome by providing a lock for each drawer, but the separate locking and unlocking of the drawers obviously is a troublesome expedient.

It is one of the objects of the present invention to overcome the objectionable features mentioned and provide a locking fixture for trunks which is adapted to secure all of the drawers of a trunk in a very simple manner by means of a single lock, and also tie the horizontal walls of the trunk together.

A further object is to so construct the locking fixture that it can be easily and most expeditiously adjusted to the drawer section.

A further object is the provision of a construction wherein the lock itself is carried directly by the lock bar.

A still further object is to provide a collapsible or hinged form of lock bar, whereby, when it is not desired to use the bar, the members or parts thereof can be folded together and placed in one of the drawers of the trunk, and whereby further the upper member of the lock bar can be swung downwardly so that access may be obtained to the upper drawers, without the necessity of disconnecting the entire bar.

With the above primary, and other incidental, objects in view, the invention consists of the devices and parts, or the equivalents thereof, as hereinafter more fully set forth.

In the accompanying drawing, Figure 1 is a front view of a wardrobe trunk provided with the improved locking fixture, a fragment of the wardrobe section being shown in dotted lines, and also shown swung to open position, and furthermore showing in dotted lines the lock bar as engaged at its lower end but its upper end swung to the right out of engagement; Fig. 2 is a vertical sectional view on the line 2-2 of Fig. 1, looking in the direction of the arrows, the said figure also showing by dotted lines the upper portion of the lock bar swung outwardly; Fig. 3 is a horizontal section on the line 3-3 of Fig. 1, looking in the direction of the arrows; Fig. 4 is a horizontal section on the line 4-4 of Fig. 1, looking downwardly in the direction of the arrows; and Fig. 5 is a detail edge view of the upper portion of the lock bar, showing the locking mechanism carried thereby.

Referring to the drawing, the numeral 6 indicates the drawer section of a wardrobe trunk, and 7 the wardrobe section thereof. The drawer section is divided horizontally medially by a partition 8 to reinforce the trunk. Drawers 9 are slidably positioned in the drawer section above and below the partition 8, and are supported by and are slideable on angle brackets 10 fastened to the side walls of the drawer section.

The lock bar for locking all of the drawers is indicated by the numeral 11. The lower end of this bar is reduced as indicated by the numeral 12, and said reduced end is adapted to releasably fit a slot 13 formed in a short arm 14 projecting outwardly from the bottom of the drawer section of the trunk.

A bracing arm 15 fastened to the front portion of the medial partition 8 projects outwardly therefrom, and on one side edge is provided with an inwardly-extending slot 16, into which the locking bar is swung to prevent outward movement thereof.

The upper portion of the front of the uppermost drawer 9 is cut away, as indicated by the numeral 17, and in this cut-away portion is secured an inwardly-depressed plate 18, the depression thereof forming a space to receive the lock 19 carried at the upper end of the lock bar. The upper portion of the lock bar is formed with a key-hole 20 registering with the key-hole 110 of the lock, to provide for the insertion of a key 21 in the lock. The bolt of the lock is

indicated by the numeral 22, and in locking position this bolt extends through an opening in the plate 18 and enters a bolt recess 23, formed on the under side of the top of drawer section 6. While the locking bar 11 may be a continuous bar, yet I prefer to construct the same of two sections hinged together at 24. By this provision, when it is not desired to use the bar, the two sections 10 or members thereof can be folded together and placed in one of the drawers of the trunk. Furthermore, by forming the bar of two members hinged together, access can be obtained to the uppermost drawers, merely 15 by unlocking the upper bar member and turning it outwardly on its hinge, as indicated by dotted lines in Fig. 2. In this way provision is made for access to the uppermost drawers without the necessity of removing or detaching the entire lock bar structure. In adjusting the bar to place, the lower reduced end 12 of said bar is first inserted through the slot 13 of arm 14. The two sections or members can then be opened 20 out to a vertically alined position, and then swung inwardly from the dotted line position shown in Fig. 1 to cause the edge of the lower member to be brought into engagement with the open-ended slot 16. The entire bar is next pulled upwardly until the lock 19 is brought into registration with the recess of the plate 18. The upper member is then pushed inwardly from its dotted line 25 position shown in Fig. 2 into engagement with the recess. The key 21 being turned the bolt 22 of the lock is forced into the bolt recess 23 so as to lock the bar, and thus lock all of the drawers against being pulled outwardly. The recess of the plate 18 not only 30 affords space for the accommodation of the lock, but furthermore acts as a support for the lock bar. Attention is also directed to the fact that the engagement of the edge of the lower member of the lock bar with the 35 open-ended slot of the bracing member 15 prevents the lock bar from being bulged or forced outwardly. If this slot 16, or its equivalent, were not provided, the lock bar would be caused to be bulged or bowed outwardly whenever the trunk is tilted, or whenever the drawer section of the trunk is 40 uppermost, with the wardrobe section resting upon the ground or other support. The drawers then would act against the lock bar, and would be movable and shiftable, to the 45 injury of the trunk.

For convenience in turning the lock bar, the upper member thereof may be provided with a suitable projecting handle 25.

60 What I claim as my invention is:

1. The combination with a trunk having a plurality of drawers, of a locking fixture therefor, comprising a two-part-hinged together member engaging the drawers and 65 releasably engaging the trunk at one end

and carrying a lock at its opposite end, the bolt of said lock, when the locking fixture is in locking position, lockingly engaging the trunk, and means engaging a medial portion of the two part member for preventing the outward movement of the medial portion of said member while in locked position. 70

2. The combination with a trunk having a plurality of drawers, of a locking fixture 75 therefor, comprising a holdable bar positioned in front of the drawers and releasably engaging the trunk at one end and carrying a lock at its opposite end, the bolt of said lock, when the bar is in locking position, 80 lockingly engaging the trunk, and means connected to the trunk and engaging a medial portion of the bar for preventing the outward movement of the medial portion of said bar while in locked position. 85

3. The combination with a trunk having a plurality of drawers, of a locking fixture therefor, comprising a foldable bar positioned in front of the drawers and releasably engaging the trunk at one end, and carrying a lock at its opposite end, the bolt of said lock, when the bar is in locking position, lockingly engaging the trunk, and a bracing arm projecting from a medial portion of the trunk, lockingly engaging 95 the bar adjacent its folding joint for preventing the outward movement of said bar while in locking position.

4. The combination with a trunk, having a plurality of drawers, one of said drawers 100 having a recessed plate secured thereto, the recess extending inwardly, of a locking fixture, comprising a foldable bar positioned in front of the drawers and releasably engaging the trunk at one end and carrying a lock at its opposite end, the said lock, when the bar is in locking position, extending into the recess of the plate, and the bolt of the lock, when the lock is within the recess, lockingly engaging the trunk, and means connected to the trunk and engaged by the bar 105 for preventing outward movement of the medial portion of the bar while in locked position. 110

5. In combination with a trunk, having 115 a plurality of drawers, of a locking fixture therefor, comprising a projecting slotted arm connected to the lower portion of the trunk, a foldable bar positioned in front of the drawers, and having a lower reduced end, the said reduced end releasably engaging the slot of the projecting arm, means connected to the trunk and engaged by the bar for preventing outward movement of the medial portion of the bar while in 120 locked position, and a locking mechanism between the upper end of the bar and the trunk. 125

6. The combination with a trunk, having a plurality of drawers, of a locking fixture 130

therefor, comprising members hinged together and engaging the drawers, the end of one hinged member releasably engaging the trunk, and the end of the other member having locking engagement with the trunk, and means connected to the trunk and engaged by the hinged members for preventing outward movement of the hinged portion of the locking member while in engagement with the trunk.

7. In combination with a trunk having a plurality of drawers, one of said drawers having a recessed plate secured thereto, the recess extending inwardly, of a locking fixture, comprising a slotted arm connected to the lower portion of the trunk, a foldable bar positioned in front of the drawers, said bar comprising members hinged together and engaging the drawers, the end of the

lower member being reduced, the said reduced end releasably engaging the slot of the projecting arm, a slotted arm connected to the trunk and engaged by the hinged member for preventing the outward movement of the hinged portion of the foldable bar while in engagement with the trunk, and a lock carried by the other hinged member, the said lock, when the bar is in locking position, extending into the recess of the plate, and the bolt of the lock, when the lock is within the recess, lockingly engaging the trunk.

In testimony whereof, I affix my signature in presence of two witnesses.

GEORGE HENRY WHEARY.
